UNITED STATES PATENT OFFICE.

ERWIN GRIESBAUM, OF ST. LOUIS, MISSOURI.

RAIL TIE.

Application filed July 13, 1927. Serial No. 205,383.

This invention relates to new and useful improvements in railway track construction and more particularly to ties for supporting and securing the rails in position.

5 The main objects of the invention are to provide a metallic tie having a plurality of points of supporting the rail and provided with a single engaging point disposed intermediate said supporting points for locking the rail to said tie.

10 Other objects of the invention are to provide a rail tie pressed out of sheet metal and provided with a series of apertures in its body portion and provided with serrated edges in its base portion to allow the material of the track bed to enter such apertures and serrations and insure a more efficient anchoring of the tie.

15 Further objects of the invention are to provide a metallic rail tie having longitudinally disposed parallel side portions spaced from each other and disposed in the same horizontal plane to form seats or two-point supports for the rail and provided with suitable means arranged intermediate said seats for receiving and locking the rail intermediate its points of support to said tie.

20 Additional objects of the invention are to provide a metallic tie having its upper face formed with upward projections disposed laterally and adapted to be engaged by the outer edges of the rail flanges to prevent spreading of the rails, and to provide means for anchoring the rail to the tie without the use of bolts, nuts, or similar fastening devices.

25 With these and other objects in view, my invention consists in certain novel features of construction and arrangement of parts, hereinafter more fully described and claimed, and illustrated in the accompanying drawings, in which—

30 Figure 1 is a top plan view, partially broken away, of my improved tie.

35 Figure 2 is a side elevational view of the same, partly broken away, and showing the rails in transverse cross section.

40 Figure 3 is an end elevational view of the tie showing portion of the rail in side elevation.

45 Figure 4 is a transverse cross section taken on line 4—4 of Figure 1.

50 Figure 5 is a detail cross section taken on line 5—5 of Figure 1 and showing portion of the rail.

Figure 6 is an end elevational view of the means utilized to anchor the rail to the tie.

55 Referring by numerals to the accompanying drawings, 10 indicates a tie which is formed of a single piece of metal, preferably sheet metal, stamped into proper shape. A blank from which the tie is made is perforated during blanking operation to provide apertures 11, longitudinally disposed elongated openings 12, and centrally and transversely disposed openings 14. The longitudinal edges of the blank are cut to provide a series of semi-circular notches 15.

60 The blank, when properly perforated, is pressed into proper shape as best shown in Figure 3, thereby providing vertically disposed sides 16 having their edges bent horizontally and outwardly to provide flanges 17 which form the necessary support for the tie.

65 The portion arranged intermediate sides 16 is shaped to provide two longitudinally disposed shoulders or ribs 18 which are arranged one adjacent to each side 16 and are provided with flat tops 19 arranged in the same horizontal plane with each other. These top portions 19 are adapted to receive and support the rail which extends transversely thereof. A centrally disposed rib or shoulder 20 is formed parallel with side portions 18 and has its top wall disposed a suitable distance below the horizontal plane of tops 19. Portions 21 uniting each side shoulder 18 with central portion 20 are formed channel-shape in cross section having a horizontally disposed bottom 22 which is arranged a suitable distance below the horizontal plane of central top 20^a and vertical sides 24 and 25 which connect with the tops 19 and 20^a, respectively.

70 Tops 19 are slit transversely as indicated at 26 and portions of said tops are pressed upwardly above the plane thereof to provide projections or lugs 27 which are disposed transversely of the tie and are designed to be engaged by the outer flanges of the rails and form stops for the latter to prevent spreading thereof.

75 When the tie is pressed, apertures 11 are disposed in the vertically presented portions of the tie, namely, sides 16 and walls 24 and 25, while the elongated openings are arranged in the horizontally disposed portions of tops 19, 20^a, and 22. These apertures and openings serve to lighten the weight of the

110

tie and also provide means through which the track bed material passes, thereby providing firm anchoring of the tie.

The centrally and transversely disposed 5 openings 14 are arranged in the top portions 20^a and are properly spaced with respect to the central line of the rail so that the base flanges thereof overlap said openings.

Extending upwardly through each pair of 10 openings are the upwardly presented portions 28 of a U-shaped clamp 29, which latter is disposed within the chamber formed by the central shoulder or rib 20 and the horizontally disposed portion 30 of clamp 29 15 bears against the underside of portion 20^a as shown in Figure 5. Clamp 29 is formed of inverted channel shape in cross section, being provided with vertically disposed marginal flanges 31. These flanges terminate substantially 20 on the same horizontal plane with the flanges of the rail, and the ends 32 of portions 28 are flangless so that they may be forcibly bent or hammered over the edges of the rail flanges as shown in full lines in Figure 5, the dotted lines showing said ends 32 in upright positions before attachment to the rail.

In this manner the rail is securely anchored to the tie at a point intermediate its 30 supporting points and a portion of said tie is placed under tension so as to securely hold the rail to its seat. Lugs 27 are arranged to each side of the anchoring means and are designed to receive the lateral pressure to 35 which the rails are subjected, thereby relieving said anchoring means of such pressure and insuring an efficient interengagement between the rail and tie at all times. When ends 32 are bent over the edges of the rail 40 flanges, the top portion 20^a is stressed and has a tendency to hold the rail to the seats.

A railway tie of my improved construction is comparatively light in weight, is of strong construction and is provided with rail 45 attaching means which can be attached and detached from position without the use of fastening devices, thereby prolonging the life of the tie. The notched edges of the base flanges of the tie allow the spiking of the tie when so desired, while when its 50 flanges are embedded in the track bed, said edges serve to hold the tie unmovable.

The tie, as well as the attaching means, can be stamped out of sheet metal, thereby enabling production thereof on a large scale and at a low cost.

Obviously various changes in the construction of my improved tie can be made without departing from the spirit of my invention.

I claim:

1. A railway tie comprising a metallic member having a pair of raised rail seats disposed near each end and spaced from each 65 other, and a U-shaped clamping member ar-

ranged against the underside of said member intermediate each pair of seats and having its end portions projecting upwardly and inwardly therefrom for engaging the edges of the base flanges of the rail and clamping the 70 latter against said seats.

2. A rail tie comprising a metallic member having a centrally and longitudinally disposed depression, thereby providing at each end of the tie a pair of spaced rail 75 seats, and a U-shaped clamping member arranged against the underside of the central portion intermediate said rail seats and having its ends projecting upwardly through openings formed therein for engaging the edges of the base flanges of the rails and clamping the latter to the tie, the top of said central portion being spaced from said rail.

3. A railway tie comprising a metallic member provided with a centrally and longitudinally disposed depression and having a plurality of spaced horizontally disposed faces arranged in pairs near each end of said tie and in the same horizontal plane with each other, whereby each rail has a two-point supporting engagement with each tie, and means engaged with said member intermediate each pair of said faces for engaging the flanges of said rail and securing it to 90 said tie.

4. A railway tie comprising a metallic member provided with a plurality of tie supporting surfaces arranged in the same horizontal plane, the top of the tie intermediate 100 said surfaces being depressed and spaced from the rail, a U-shaped clamping member arranged against the underside of said depressed portion and having its ends projecting upwardly through openings formed therein, said ends being adapted to be bent 105 over the edges of the flanges of the rail for securing the latter in position.

5. A railway tie comprising a metallic member provided with a plurality of tie supporting surfaces arranged in the same horizontal plane, the top of the tie intermediate 110 said surfaces being depressed and spaced from the rail, a U-shaped clamping member arranged against the underside of said depressed portion and having its ends projecting upwardly through openings formed therein, said ends being adapted to be bent 115 over the edges of the flanges of the rail for securing the latter in position, and lugs projecting upwardly and transversely in spaced 120 relation with said rail surfaces for engaging the outer edges of the flanges of said rails and preventing spreading of said rails laterally.

6. A metallic railway tie comprising a metallic member provided with a plurality of spaced tie supporting faces arranged in the same horizontal plane with each other, the top of said member intermediate said 125 faces having a depressed portion disposed 130

below the horizontal plane of said faces, said depressed portion being provided with a pair of openings arranged one at each side of each rail, and a U-shaped member placed 5 against the underside of said depressed portion and having its ends projecting upwardly through said openings at each side of the rail flange and adapted to be hammered over the edges thereof for securing said rail to 10 said tie.

7. A metallic railway tie comprising a pair of vertically disposed sides having its edges disposed horizontally and outwardly to form a base for said tie and having its 15 top provided with two series of surfaces disposed in different horizontal planes, one series being arranged in spaced relation with each other to provide a pair of spaced rail seats near each end of the tie and the other 20 series being disposed below the horizontal plane of the first series and intermediate each pair of said rail seats whereby the base of the rail is spaced from the top of said second series, and means extending upwardly from the last-mentioned series of surfaces 25 and adapted to engage the flanges of each rail for securing the latter against said rail seats.

8. A metallic rail tie comprising a pair of 30 vertically disposed sides having its edges disposed horizontally and outwardly to form a base for said tie and having its top provided with two series of surfaces disposed in different horizontal planes, one series being 35 arranged in spaced relation with each other to provide a pair of spaced rail seats near each end of the tie and the other series being disposed below the horizontal plane of the first series and intermediate each pair of 40 said rail seats whereby the base of the rail is spaced from the top of said second series, and means extending upwardly from the

last-mentioned series of surfaces and adapted to engage the flanges of each rail for securing the latter against said rail seats, and 45 projections arranged adjacent to each rail seat for engaging the edge of the outer flange of each rail to prevent spreading of said rails.

9. A metallic rail tie formed of sheet 50 metal pressed to provide a pair of vertically disposed sides having its edges disposed horizontally and outwardly to form the base for the tie and having its top formed to provide a pair of longitudinally disposed spaced ridges, and a centrally and longitudinally disposed ridge, the latter being disposed below the plane of the first-mentioned ridges, the side ridges forming spaced seats for the rails and the central ridge being provided with openings, and means extending through said openings for engaging the edges of the flanges of each rail and securing the latter against the seats formed in said side ridges, the body portion of said tie being provided with suitable openings for receiving the track bed material and anchoring said tie in 55 position.

10. As a new article of manufacture, a rail tie comprising a metallic member of inverted U-shape in cross section and provided in its web portion with a plurality of rail supporting faces arranged in the same horizontal plane, the portion intermediate said faces being depressed, and lugs projecting upwardly from said web portion and disposed transversely in spaced relation with said rail supporting faces and adapted to engage the outer edges of the flanges of rails to prevent spreading of said rails laterally. 60

In testimony whereof I hereunto affix my signature this eighth day of July, 1927.

ERWIN GRIESBAUM.
